UNITED STATES PATENT OFFICE.

JOHN HURLEY, OF LITTLEFALLS, NEW YORK.

LEATHER-STRETCHING HOOK.

SPECIFICATION forming part of Letters Patent No. 747,480, dated December 22, 1903.

Application filed October 12, 1903. Serial No. 176,600. (No model.)

To all whom it may concern:

Be it known that I, JOHN HURLEY, a citizen of the United States, residing at Littlefalls, in the county of Herkimer and State of New York, have invented certain new and useful Improvements in Leather-Stretching Hooks, of which the following is a specification, such as will enable those skilled in the art to which it appertains to make and use the same.

10 The object of this invention is to provide an improved hook or hockel for use in stretching leather from which it is desired to make belts and other articles; and with this and other objects in view the invention consists in 15 a device of the class specified constructed as hereinafter described and claimed.

The invention is fully disclosed in the following specification, of which the accompanying drawings form a part, in which the separate parts of my improvement are designated by suitable reference characters in each of the views, and in which—

Figure 1 is a perspective view of a leather-stretching hook made according to my invention; Fig. 2, a bottom plan view of a part of a frame and showing the method of using my improved leather-stretching hook; Fig. 3, a detail view showing the method of connecting one of my hooks with a sheet of leather, 30 and Fig. 4 a section on the line 4-4 of Fig. 2 and showing a slight modification in the form of the hook.

In the practice of my invention I provide a hook or hockel for the purpose specified 35 which comprises a transverse flat bar a , provided at one side and centrally thereof with a projecting arm a^2 and on the opposite side and at right angles to said arm with a longitudinal hook member a^3 , which is flat and 40 parallel with and extends over the bar a and is wider than the arm a^2 .

In Figs. 2 and 3 of the drawings I have shown at b a part of a sheet of leather which it is desired to stretch, and in practice I form 45 adjacent to one edge thereof a slot or opening b^2 parallel with said edge and through which the arm a^2 is adapted to be passed. In connecting the hook or hooks with the leather the arm a^2 is passed clear through the slot or 50 opening b^2 , and the edge of the leather is folded over, as shown at b^3 in Fig. 2, so that the free edge or fold is caught in the hook a^3 in the manner shown in Fig. 2.

In the form of construction shown in Fig. 1 the arm a^2 is provided with an opening at 55 a^4 , through which a cord or similar device c is passed and secured in any desired manner, and in practice a suitable frame d is provided, and to this frame is secured a plurality of winches or similar devices e , around which 60 the cords c are passed. Any suitable style or form of frame may be provided, and the sheet b of leather is placed thereon or thereover, and the hooks a , any desired number of which may be employed, are connected with the 65 leather, as described, and sufficient power is applied to the cords c to stretch the leather to any desired extent. The ends a^5 of the cross-bar a of the hook or hockel when the device is connected with the leather, as shown 70 and described, catch in or operate in the fold of the leather at b^4 on both sides of the slot or opening b^2 , and this prevents the hook or hockel from tearing out, and these ends a^5 may be made of any desired length. 75

Instead of forming the hole at a^4 in the arm a^2 , by means of which the cord c or other flexible device may be connected therewith, I may provide said arm with a hook, as shown at a^6 in Fig. 4, and the cord or other device 80 may be connected with said hook.

My improved hook or hockel may be stamped from heavy sheet-steel, or it may be cast or formed in any other desired manner.

Having fully described my invention, what 85 I claim as new, and desire to secure by Letters Patent, is—

A leather-stretching hockel comprising a flat bar provided at one edge and centrally thereof and at right angles thereto with a 90 projecting arm, and at the opposite edge with an elongated hook at right angles to said arm and which extends over said bar and is flat and parallel therewith, substantially as shown and described. 95

In testimony that I claim the foregoing as my invention I have signed my name, in presence of the subscribing witnesses, this 7th day of October, 1903.

JOHN HURLEY.
